ATTORNEY.

UNITED STATES PATENT OFFICE

VIOLA McPHILLIPS, OF MEMPHIS, TENNESSEE.

RADIATOR ORNAMENT

Application filed August 19, 1929. Serial No. 386,983.

My said invention relates to an illuminated ornament and it is an object of the same to provide a device for location on an automobile radiator which shall preferably consist 5 of a hollow translucent figure suitable to the Christmas season, though other devices symbolic of other holidays or seasons are within the scope of my invention.

Referring to the drawings, which are made 10 a part of this application and in which similar reference characters indicate similar parts:

Fig. 1 is a perspective of my device,

Fig. 2 a vertical section showing the interior construction, and

Fig. 3 a detail in plan of a part of a bracket.

In the drawings, reference character 10 indicates a bracket in the form of a strip of sheet metal for attachment to a radiator cap, this bracket having an opening 11 through 20 which a bolt at the top of the cap may pass, though other methods of attachment may be used. Near the end the farthest from opening 11 I have provided another opening to receive a bolt 12 said bolt also passing through 25 an opening in a suitable figure or symbol 13, here shown as consisting of a representation of Santa Claus. The various parts of the figure may be suitably colored in obvious 30 manner though no claim is made to any particular coloring or any particular figure or symbol. As here shown at 14 and 15 in Fig. 2 a part of the figure between the feet is flattened at opposite sides to provide a flat 35 face against which the head of the bolt may rest and another flat face resting against a step formed by the lower-most part of strip 10. Other parts of the figure also rest against the bracket as indicated at 16 and the bottom 40 of the figure rests on the extension 17 of the bracket, all with the purpose of providing a secure and steady engagement of the figure with the bracket so that it will not be loosened by the vibration of the automobile.

45 An angle iron 18 is secured to the bracket

in any suitable manner, this iron being shown here as having a part extending upward for pivoted attachment, as by means of a rivet, of another angle iron 19 forming a part of a socket 20 adapted at one end for attachment 50 of an electric light socket 21 and at the other end formed to receive a bulb 22. The socket extends into an opening at 23 so that the bulb will be located inside the figure. The plug is connected by a conductor 24 to any suitable 55 source of electricity whereby the bulb may be lighted to illuminate the interior of the figure, with results that will be obvious.

My device may be changed in many respects all without departing from the spirit 60 of the invention and therefore I do not limit myself to what is shown in the drawings and described in the specification but only as indicated in the appended claims.

Having thus fully described my said invention, what I claim as new and desire to secure by Letters Patent is:

1. A radiator ornament comprising a hollow symbolical figure of translucent material, a bracket adapted to be supported on an automobile radiator, means for attaching the figure to the bracket, means on the bracket for supporting an electric lamp within said figure, and means for connecting the lamp to a source of current; substantially as set 75 forth.

2. A radiator ornament including a bracket consisting of a flat metal strip having a perforation at one end to fit on the neck of a radiator and bent at the other end to form 80 a step, a hollow symbolical figure standing on the step, a bolt securing the figure releasably to a downwardly extending portion of the strip, a socket on an intermediate portion of the strip extending into an opening 85 in said figure, and a bulb supported by said socket within said figure, substantially as set forth.

3. A radiator ornament including a bracket 90 consisting of a flat metal strip having a per-

foration at one end to fit on the neck of a radiator and bent at the other end to form a step, a hollow symbolic figure standing on the step, a bolt securing the figure releasably to a downwardly extending portion of the strip, an angle iron on an intermediate portion of the strip, a second angle iron connected to the first for adjustment about a horizontal axis, a socket on the second angle iron, and a bulb supported by said socket within said figure, substantially as set forth.

In testimony whereof I affix my signature.
VIOLA McPHILLIPS.
